Attorney:

UNITED STATES PATENT OFFICE.

FRED McALISTER, OF NIAGARA, NORTH DAKOTA.

TRACE-HOLDER.

1,321,138.

Specification of Letters Patent. Patented Nov. 11, 1919.

Application filed July 11, 1919. Serial No. 310,129.

To all whom it may concern:

Be it known that I, FRED McALISTER, a citizen of the United States, residing at Niagara, in the county of Grand Forks, 5 State of North Dakota, have invented certain new and useful Improvements in Trace-Holders; and I do hereby declare the following to be a full, clear, and exact description of the invention, such as will enable 10 others skilled in the art to which it appertains to make and use the same.

This invention relates to trace holders and it has for its object to provide a construction that will comprise a minimum of parts 15 and in which the actuating spring for the keeper may be readily renewed when broken but will nevertheless be securely protected from extraneous influences. A further object of the invention is to provide an article 20 that will be economical of manufacture.

In the drawings:

Figure 1 is a side elevation of a trace holder embodying the present invention.

Fig. 2 is a vertical longitudinal section, 25 illustrating the arrangement of the spring.

Fig. 3 is a top plan view.

Fig. 4 is a vertical transverse section in the plane of the pivot of the keeper.

Referring to the drawings, the present 30 holder comprises a base adapted at its ends to receive the bolts that secure it to a shaft and rising from this base 5, adjacent one end is a hook finger 6, the upper end of which is convexed and the extremity of which 35 ranges in the direction of the opposite end of the base.

Spaced from the hook finger 6 and substantially midway of the ends of the base is a pair of laterally spaced and upwardly 40 directed ears 7 having registering transverse perforations 8 for a purpose to be presently described.

Adjacent to the opposite end of the base from the hook finger, is an upwardly directed and transversely curved or arc-shaped flange 9.

In practice the base plate 5 is secured with the bill of the hook 6 directed forwardly so that the trace, which is engaged 50 over the hook finger, pulls into the concavity of the latter and to prevent disengagement

of the trace accidentally when it is slack, there is provided a keeper.

The keeper consists of a lever 10 having a narrowed depending ear 11 that is disposed between the ears 7 and is adapted to rock upon a pivot pin 12 passed through the perforations 8 and a corresponding perforation 13 in the depending ear. One end of this keeper lever overlies the upper convexed end face of the hook finger 6 and is provided with a concavity 14 to receive snugly the said face. To hold the lever normally and yieldably in this position, a helical spring 15 has one end seated in a recess 16 in the base plate 5 between the bottoms of the ears 7 while its other end is seated in a recess 17 in the lower face of the corresponding portion of the lever, between the ears 7 and the flange 9.

To protect the helical spring against extraneous influences, the corresponding extremity of the keeper lever 11 is provided with a depending apron 18 that lies at all times with its lower edge portion within the curvature of the flange 9 and in close proximity to it, forming in connection with the flange, a baffle at the corresponding side of the spring and from which direction injury is most apt to come to the spring as the vehicle advances.

The form and position of the flange 9 as well as the adjacent end of the lever 11, is such that when the lever is swung upwardly under the influence of such rearward strains as may come to it at any time, this end face of the keeper lever will impinge against the flange 9 which latter will then relieve the pivot pin of over-strain.

What is claimed is:—

In a trace holder the combination with a base plate having a hook finger at one end, a transversely arc-shaped flange rising from the same face of the plate at its opposite end, the hook finger and the flange 95 having their concavities directed toward each other, and a pair of spaced ears between the hook finger and the flange, of a keeper lever having a depending ear pivoted to and between the ears of the base plate and 100 having one end concaved and arranged to receive in its concavity the outer end face

of the hook finger, the other end of the lever having an apron arranged and shaped to conform to and fittingly contact with the concave face of the flange throughout the movement of the lever, and a helical spring disposed and held between the aproned end of the lever and the base plate.

Copies of this patent may be obtained for five cents each, by addressing the "Commissioner of Patents, Washington, D. C."

In testimony whereof, I affix my signature in the presence of two witnesses.

FRED McALISTER.
